Des. 177,180

Patented Mar. 20, 1956

177,180

HEAD SCARF

Erwin B. Jackman, Brooklyn, N. Y.

Application January 26, 1954, Serial No. 28,679

Term of patent 7 years

(Cl. D3—13)

FIG.1.

FIG. 2.

FIG. 3.

FIG.4.

Fig. 1 is a plan view of a head scarf showing my new design;

Fig. 2 is a front elevational view thereof as it appears in wearing position;

Fig. 3 is a rear elevational view; and

Fig. 4 is a side elevational view thereof.

I claim:

The ornamental design for a head scarf, substantially as shown.
